PANEL.

No. 16,357

Patented Oct. 27, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,357, dated October 27, 1885.

Application filed July 18, 1885. Serial No. 172,007. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design is intended for an ornamental panel such as is used for doors, wainscots, &c.; and it consists in three parts: first, a central circular figure, A, and a rectangular flat space, B, surrounding said figure, these portions being formed upon the frusto-pyramidal elevation C. At the corners of said elevation C are four rectangular pyramids, D, and between said pyramids are elongated pyramidal elevations O. The design thus formed is duplicated at the opposite end of the panel to form the second part. The third part of my design consists in the elongated rectangular frusto-

pyramidal elevation E, and on each side thereof an elongated pyramidal elevation, F. The elevations E and F are disposed, as shown, between the first and second parts of my design, 25 and forming the middle portion of the panel. Between the various elevations are longitudinal channels G H and transverse channels I J K L M N.

I claim—

The design for a panel, substantially as herein shown and described, consisting in the two end portions, each containing the elevations C, having flat upper portions, B, with ornamental figure A thereon, with the elevations 35 D and O, and the middle portion consisting of the elevations E and F and the intermediate channels, G H I J K L M N.

FREDERICK MANKEY.
